UNITED STATES PATENT OFFICE.

CHARLES THOMAS MASON, OF SUMTER, SOUTH CAROLINA, ASSIGNOR TO SPLITDORF ELECTRICAL COMPANY, OF NEWARK, NEW JERSEY, A CORPORATION OF NEW JERSEY.

IGNITION APPARATUS FOR INTERNAL-COMBUSTION ENGINES.

1,390,574.

Specification of Letters Patent. Patented Sept. 13, 1921.

Original application filed November 18, 1918, Serial No. 263,027. Divided and this application filed October 1, 1920. Serial No. 414,052.

To all whom it may concern:

Be it known that I, CHARLES T. MASON, a citizen of the United States, residing at Sumter, in the county of Sumter, State of South Carolina, have invented certain new and useful Improvements in Ignition Apparatus for Internal-Combustion Engines, of which the following is a description, reference being had to the accompanying drawing and to the figures of reference marked thereon.

The invention relates to new and useful improvements in an ignition apparatus for internal combustion engines, and more particularly to the manner of supporting the generating coil, and providing the distributor which is associated therewith.

An object of the invention is to provide a magneto electric device for an ignition system wherein the generating coil, the condenser, and the distributor points are all mounted on a unitary structure so that said parts may be removed as a unit and replaced in the magneto at will.

A further object of the invention is to provide a distributor for a magneto ignition device which includes a set of contacts connected to the generating winding of the magneto, and a second set of contacts associated therewith, and an oscillating means for connecting a contact of the first set with a contact of the second set, and then the other contact of the first set with the other contact of the second set.

These and other objects will in part be obvious and will in part be hereinafter more fully disclosed.

In the accompanying drawings:—

Figure 1 is a longitudinal sectional view through a magneto electric generator having my improvements embodied therein;

Fig. 2 is a view showing more or less diagrammatically the rotor, the generating coil and the distributor, and

Fig. 3 is a diagrammatic view showing the relation of the rotor to the pole pieces, and the generating coil also to the interrupter and to the distributor.

The magneto electric generator shown in detail in the drawings, is shown, described and claimed in my co-pending application, Serial Number 263,027, filed November 18, 1918, of which the present application is a

division. The magneto generator includes a supporting base 1 on which is mounted a permanent magnet 2. A rotor 3 is preferably connected to the engine shaft so as to rotate at half speed and this rotor is carried by the shaft 4 which runs in ball bearings 5 and 6. The ball bearing 5 is mounted in a holder 7, while the ball bearing 6 is mounted in the holder 8. Suitably mounted on the base 1 are pole pieces 9 and 10. These pole pieces support a core 11, on which is mounted a primary generating coil 12 and a secondary generating coil 13. Associated with the generating coils and supported by structures carried by the core 11 is a condenser 14. The core is removably secured to the pole pieces 9 and 10, so that the generating coil may be readily removed from the magneto and when the coil is removed the condenser will be removed therewith.

The pole pieces 9 and 10 are provided with pole faces 15 and 16, which coöperate with the lobes of the rotor. The rotor 3 is provided with two pairs of lobes 18, 19, and 20, 21. The rotor turns in the direction of the arrow, as indicated in the figures of the drawings. Let us suppose that the lobes 20 and 21 are the N. lobes, while the lobes 18 and 19 are the S. lobes. The N. lobes are so placed that the angle from center to center is $180^\circ - \frac{X^\circ}{2}$ where X is the angular displacement between the engine cylinders. The S. lobes are similarly disposed. When the rotor is in the position shown in Fig. 3, the lobes 18 and 20 are breaking from the pole faces 15 and 16, respectively, and at this time there is a maximum current generation in the primary coil. An interrupter is in circuit with the primary coil and is so timed as to break the circuit just at this maximum period of current generation.

The interrupter is shown more or less diagrammatically in the drawings and consists of a cam 22, mounted on the shaft 4, which operates on a fiber block 23, carried by an arm 24, on which is mounted one of the contacts 25 of the interrupter. The other contact 26 of the interrupter is stationary. The primary circuit is indicated at P in Fig. 3 of the drawings, and it will be noted that this primary circuit is connected to the fixed contact of the interrupter. The other con-

tact of the interrupter is grounded. In Fig. 3 of the drawings, the cam 22 turns in the direction of the arrow and is about to lift the arm 24 and separate the contacts to break the primary circuit. This occurs, as above noted, just as the lobes 18 and 20 are breaking away from the pole faces 15 and 16.

Also, associated with the rotor, as above noted, is a distributor. This distributor includes a lever 27, which is mounted on a hardened steel pin 28, carried by the bearing holder 7. The lever 27 is actuated by an eccentric 29, carried by the shaft 4. Adjacent the upper end of the lever 27 there is a metallic strip 30, which is adapted to coöperate with the pins 31 and 32. Also carried by this lever 27 is a metallic strip 33, which is adapted to coöperate with the pins 34 and 35. These pins are mounted in a fiber block, which is mounted on a single structure supported by the core of the coil, so that the fiber block, the coil and the condenser are all removed as a unit without requiring any disconnection of the pins in the fiber block with the generating coil. The pins 31 and 34 are connected to a bar 36, which in turn is connected to the secondary generating coil. The pin 32 is connected to a terminal 37 which in turn is connected with one of the spark plugs and the pin 35 is connected with a terminal 38, which in turn is connected with the other spark plug. The two spark plugs are indicated at S and S', in Fig. 3 of the drawings. Inasmuch as the lever 27 is swung by an eccentric member and the metallic strips 30 and 33 will yield to a certain extent after brought into engagement with the pins, this lever 27 is so timed as to swing into contact with the pins first to the right, as viewed in Fig. 3 and then the pins at the left, and will remain in contact with said pins during a considerable time interval. In other words, the eccentric is at a dwell, so far as movement is imparted to the lever 27, while the metal strips are in contact with the pins. This long time interval permits a wide range in the time interval of the spark. Furthermore, inasmuch as the circuit between the secondary coil and the spark plug S', for instance in Fig. 3, is broken at two points, the spark, in order to jump to the wrong cylinder, must cross this double air gap and this insures that the spark will pass to the right cylinder only, even though the lever 27 be given a comparatively short swing.

The parts are shown in position in Fig. 3 for producing the spark at the spark plug S', and the contacts are just about to separate to interrupt the primary circuit to bring about the spark at this plug. When the rotor turns through a partial rotation, so as to bring the lobe 18 into position to break away from the pole face 15, the lobe

21 is bridging the air gap between the pole faces and the cam 22 is now positioned so as to close the contacts and said contacts remain closed during this interrupting of the flux flow through the generating coil and no spark is produced. When the rotor is turned through an angular distance from the position shown in Fig. 3 of $180^\circ - \frac{X}{2}$, and the interrupter cam is in position so as to separate the contacts 25 and 26 and break the primary circuit. At this time the lever 27 is shifted to the extreme left-hand position and the metallic strip 33 is in contact with the pins 34 and 35, so that a spark is produced at this time at the spark plug S'. A continued movement of the rotor brings the lobe 19 to a position where it breaks away from the pole face 15, but at this time the interrupter is closed and no spark is produced. When the rotor turns to the position shown in Fig. 3, it has turned through an angle of $180^\circ - \frac{X}{2}$ from the position of last spark. It will thus be seen that by the positioning of the lobes of the rotor, I am able to secure an intermittent completing of the path of the flux rotated by the rotor through the generating coil at unequal angular intervals and also at angular intervals corresponding to the angular intervals between the cylinders in the engine. It will also be noted that the generating coil is stationary and may be readily removed with the condenser and the distributor terminals without disconnecting any parts thereof.

It is obvious that minor changes in the details of construction and the arrangement of parts may be made without departing from the spirit of the invention as set forth in the appended claims.

Having thus described the invention, what I claim as new and desire to secure by Letters Patent, is—

1. An ignition generating device comprising a rotor, pole pieces associated with the rotor, a core mounted on the pole pieces, a generating coil mounted on the core, a distributor including a vibrating lever, pins associated with said vibrating lever and connected with the generating coil, means for supporting said pins, said supporting means for the pins being carried by a structure supported on the core, whereby the generating coil and the distributor pins may be removed as a unit.

2. In a magneto generator, a distributor comprising a set of contacts, a generating winding connected thereto, a second set of contacts associated with the first named set of contacts, and oscillating means for connecting one of the first mentioned contacts with one of said second mentioned contacts.

3. In a magneto generator, a distributor comprising a set of contacts, a generating

winding connected thereto, a second set of contacts associated with the first named set of contacts, and oscillating means for connecting a contact of the first set with a contact of the second set and then the other contact of the first set with the other contact of the second set.

4. In a magneto generator, a distributor comprising a set of contacts, a generating winding connected thereto, a second set of contacts associated with the first named set of contacts, and oscillating means for connecting one of the first mentioned contacts with one of said second mentioned contacts, 10 said oscillating means including a pivoted lever, an eccentric for oscillating said lever,

and yielding means carried by the lever for engaging the contacts.

5. In a magneto generator, a distributor comprising a plurality of contacts, a generating winding connected thereto, a plurality of terminals and a contact associated with each one, oscillating means for connecting a contact leading to the generating winding with a contact leading to a terminal, said 20 oscillating means including a pivoted lever, an eccentric for oscillating the lever, and yielding members carried by the lever and operating alternately to bridge the contacts.

In testimony whereof I affix my signature. 30

CHARLES THOMAS MASON.
